UNITED STATES PATENT OFFICE.

FRANK B. CROOKS, OF LOS ANGELES, CALIFORNIA.

BUTTON.

SPECIFICATION forming part of Letters Patent No. 390,209, dated October 2, 1888.

Application filed May 7, 1888. Serial No. 273,094. (No model.)

To all whom it may concern:

Be it known that I, FRANK B. CROOKS, a citizen of the United States, residing at Los Angeles, in the county of Los Angeles and State of California, have invented a new and useful Improvement in Cuff and Collar Buttons, of which the following is a specification.

My invention pertains to buttons having hinged bottoms, and relates particularly to improvements in that class of buttons in which the bottom is formed of two bent leaves hinged at the point of the bend to the shank of the button. One of the difficulties to be overcome in such buttons is the liability of the leaves to turn sidewise against the shank when being inserted in the button-hole. Various devices have heretofore been employed to avoid this difficulty.

My invention consists of the neat and simple means employed by me to avoid this difficulty.

My invention is illustrated in the accompanying drawings, which are considerably enlarged for clearness.

Figure 1 is a plan view of the bottom of the button. Fig. 2 is a cross-section of the button on line xx , Fig. 1, showing the button ready to be inserted in the button-hole.

A is the shank of the button. B B are the arms of the bent leaves which form the bottom of the button. The shank is provided with a stud, C, projecting outward from the hinge H of the shank in line with the axis of the shank. The arms B B of the bent leaves hinged to the

shank are provided upon their outer faces with depressions D D, coinciding in lateral position with the stud and equal in depth to half the thickness of the stud to receive the stud when the leaves are turned to be inserted into the button-hole, as shown in Fig. 2, and allow the outer faces of the arms B B to meet.

When it is desired to insert the button in the button-hole, the arms B B are pressed toward each other and the bottoms of the depressions D D come into contact with the stud C and prevent the arms from swinging past the axial line of the shank, but allow the outer faces of the arms to fit, and are allowed to fit closely together, so that the arms may be easily inserted in the button-hole.

Now, having described my invention, what I claim as new, and desire to secure by Letters Patent, is—

In a cuff-button such as set forth, the combination of the shank provided with the stud C, projecting outward from the hinge of the shank in line with the axis of the shank, and the arms B B of the bent leaves hinged to the shank and provided on their outer faces with depressions D D, coinciding in lateral position with the stud and being equal in depth to half the thickness of the stud.

FRANK B. CROOKS.
